UNITED STATES PATENT OFFICE.

FRANK MONK, OF CINCINNATI, OHIO.

LEATHER-SCOURING MACHINE.

SPECIFICATION forming part of Letters Patent No. 427,101, dated May 6, 1890.

Application filed June 10, 1889. Serial No. 313,719. (No model.)

To all whom it may concern:

Be it known that I, FRANK MONK, a citizen of the United States, residing at Cincinnati, in the county of Hamilton and State of Ohio, 5 have invented a new and useful Improvement in Leather-Scouring Machines, of which the following is a specification.

My invention relates to that class of machines used for scouring hides in the process 10 of manufacturing leather; and it consists in certain improvements, hereinafter described and claimed.

In the drawings, Figure 1 is a cross-section 15 of a scouring-machine embodying my invention. Fig. 2 is a rear view of the machine, the position of the operator being considered as the front of the machine. Fig. 3 is a view, partly in section, of a yielding push-rod.

A represents a frame, in which is mounted 20 a revolving scouring-cylinder B, provided with abrading-ledges b, of stone or other suitable material, and brushes b'.

C is a shield or guard for the scouring-cylinder, and D a frame, in which is mounted a 25 platform or plate E, preferably curved, which serves to support the hide and hold it in contact with the cylinder during the scouring operation. One edge of the pressure-plate E is pivotally attached to the frame, as at e.

30 F is a foot-lever fulcrumed at f, and having pivotally attached to its end one part G of a sectional yielding push-rod. The other part

G' of the push-rod is pivotally attached to the pressure-plate at e'. The part G has a sleeve g, into which takes a dowel-pin g' upon the 35 section G'. H is a rubber sleeve taking over and extending somewhat above the sleeve g. Both parts of the push-rod are provided with flanges g².

The operation is as follows: The hide is 40 placed over the pressure-plate and brought into contact with the brushes and abrading-ledges on the revolving cylinder by pressing upon the foot-lever, and thereby raising the pressure-plate. The yielding push-rod 45 permits the pressure-plate to yield and adjust itself to any irregularities or differences in thickness in the hide which is being treated, and prevents injury from a too positive engagement with the abrading-ledges. 50

It is obvious that a spiral spring may be used in place of the rubber sleeve.

I claim as my invention—

The combination, in a leather-scouring machine, of a rotating scouring-cylinder B, a 55 pressure plate or table E, pivotally mounted at one end, a foot-lever F, a yielding push-rod G G', connecting the pressure-plate and the foot-lever, and a spring H, interposed between the foot-lever and the pressure plate or table. 60

FRANK MONK.
